Primary Examiner — Cynthia R Underwood*(74) Attorney, Agent, or Firm* — Vladimir Postnikov(57) **CLAIM**

The ornamental design for a tablet case with keyboard, as shown and described.

DESCRIPTION

FIG. 1 is a front elevation view of a tablet case with keyboard showing the new design;
 FIG. 2 is a back elevation view thereof;
 FIG. 3 is a left-side view thereof;
 FIG. 4 is a right-side view thereof;
 FIG. 5 is a top plan view thereof;
 FIG. 6 is a bottom plan view thereof;
 FIG. 7 is a perspective view thereof;
 FIG. 8 is another perspective view thereof;
 FIG. 9 is a perspective view thereof in a rotated position;
 FIG. 10 is a perspective view thereof in a closed position; and,
 FIG. 11 is another perspective view thereof in a closed position.
